W. HOLTÖRP.
CIRCULATING LUBRICATION.
APPLICATION FILED JULY 2, 1920.

Patented Nov. 15, 1921.

UNITED STATES PATENT OFFICE.

WILHELM HOLTORP, OF HAMBURG, GERMANY.

CIRCULATING LUBRICATION.

1,897,050.

Specification of Letters Patent. Patented Nov. 15, 1921.

Application filed July 2, 1920. Serial No. 393,747.

To all whom it may concern:

Be it known that I, WILHELM HOLTORP, a citizen of the German Empire, residing at Hamburg, Germany, have invented certain 5 new and useful Improvements in Circulating Lubrication, (for which I have filed applications in Germany April 9, 1918; in Switzerland June 6, 1919; in Sweden June 14, 1919, and in Denmark June 20, 1919,) of 10 which the following is a specification.

My invention refers to the lubricating of bearings and more especially crank shaft bearings.

As is well known circulating lubrication 15 has been employed in vertical piston engines, for which the oil is brought to the supporting face from a tank, is collected during the rotation of the shaft in chambers arranged in the pressureless zone of the supporting face and from these is pressed back 20 into the tank. The collecting chamber of these appliances is arranged diametrically in horizontal position. Circulating lubrication systems thus arranged cannot be made use 25 of for any engines in which the pressureless parts of the bearing are arranged otherwise than horizontally *e.g.* vertically and diametrically, and in which a certain direction of 30 rotation does not prevail as in these cases the diametrical arrangement of the collecting chambers in the pressureless zones does not allow of a correct guiding and distributing of the oil.

My invention intends to apply the advantages of arranging collecting chambers in 35 the box surface to bearings in which the parts remaining pressureless are arranged otherwise than horizontally and in which the shaft has not an exclusive direction of rotation.

For this purpose two separate oil collecting chambers are arranged in the upper part 40 of the box, one or the other of which according to the direction of rotation of the shaft and of the insuing different direction 45 of the oil flow is fed with the oil flowing from the tank. The oil is pressed into one of the oil collecting chambers by the rotating of the shaft, from there into the other 50 oil collecting chamber and from there back into the oil tank.

In order to prevent the fresh oil from mixing with the circulating oil and from being thus soiled it appears advisable to divide the oil tank in two compartments in 55 such a manner, that one serves as oil cham-

ber for the circulating oil, the other to hold the fresh oil. The chambers are connected in such a way that the fresh oil may flow into the circulating oil, but not the circulating oil into the fresh oil, and that independently from the fresh oil tank oil may be introduced into the circulating lubrication system.

In the drawings affixed to this specification two modifications of the object of this invention are illustrated. They shown in—

Figure 1 a vertical section of a bearing,

Fig. 2 the upper half of the box as seen from underneath,

Fig. 3 the lower half of the box as seen from above,

Fig. 4 is a vertical cross-section of the bearing bush,

Fig. 5 a vertical section on a larger scale 75 through another modification, in which one oil chamber is provided for the circulating oil and another one for the fresh oil,

Fig. 6 a section following line A—B in Fig. 5.

In the construction according to Figs. 1 to 4 the oil tank is signified by *a*, the body of the bearing by *b* and the box of the bearing by *c*. In the upper part of the box the two separate oil collecting chambers *d* and *e* are arranged, in the lower part the oil collecting chamber *f*. The connection between the upper oil collecting chambers and the lower one is made by the lateral grooves *g* and *h*. For introducing the oil from the oil tank *a* 90 into the oil collecting chambers *d* and *e* oil tubes *l*, *m* are provided, which give into channels *n*, *o* arranged in the body *b* of the bearing.

In the construction according to Figs. 5 95 and 6, in which one oil chamber is provided for the circulating oil and another one for the fresh oil, a boss *p* is arranged in the fresh oil chamber which is bored right through to the body of the bearing and 100 closed at the bottom by a piece of tube *q* containing the oil channels *l*, *m*. From above the guide *s* of a valve *t* pressed up by a spring *r* extends into the boss. The spring rests upon the piece of tube *q*. The valve 105 guide *s* combined with boss *p* and tube *q* form a chamber *u*. The guide *s* is flattened in one place, so that between it and the wall of boss *p* a passage *v* is formed through which the oil from chamber *u* can enter the 110 chamber *a*.

Besides in the seat of valve *t* bores *w* are

provided through which oil may be directly poured into chambers *a*.

When the shaft rotates in the direction marked by an arrow the oil (in the construction according to Figs. 1 to 4) flows from tank *a*, in the construction according to Figs. 5 and 6 from chamber *a*—into which it gets through passage *v* by the movements of the bearing or by direct injection through 10 the openings *w*—through the oil channel *l* and channel *n* into the oil collecting chamber *d*, from which it is brought next into the lower collecting chamber by the influence of the rotating shaft *f*, thus effecting a thorough lubrication of the shaft. The oil trying to escape sidewise is collected by the grooves *g* and *h* and brought into the oil collecting chambers *f* and *e*, from where it is pressed back through channel *o* and channel 15 *m* into tank *a* (Fig. 2) or chamber *a* (Fig. 5). When the engine rotates in opposite direction the oil is led in opposite direction by the shaft and thus gets through channel *m* and channel *o* into the collecting chamber *e*. 20 From there it gets into the collecting chamber *f*, then into the collecting chamber *d* and back into tank *a* (Fig. 1) or chamber *a* (Fig. 5) through channel *n* and tube *l*.

By arranging two separate oil collecting chambers in the upper of both pressureless parts of the inner surface of the box the lubrication is absolutely independent upon the direction of rotation of the engine.

In the modification according to Figs. 5 and 6 chamber *a* receiving the circulating oil prevents it from mixing with the fresh oil contained in chamber *u* and the latter from being soiled. The fresh oil enters chamber *a* through passage *v* by being splashed against 30 the wall of guide *s* by the movements of the bearing and thus entering the passage in about such quantities as are needed to cover the loss.

I claim:

45 1. In a device of the kind described in combination, a bearing, a rotary part located in said bearing, an oil tank on said bearing, means for causing the oil to circulate between said tank and said bearing and two separate oil collecting grooves in the non-loaded portion of said bearing, each one

adapted to collect the oil at a certain direction of rotation.

2. In a device of the kind described in combination, a bearing, a rotary part located 55 in said bearing, an oil tank on said bearing, means for causing the oil to circulate between said tank and said bearing, an oil collecting groove in the loaded portion of said bearing, lateral grooves extending from said 60 collecting groove upward and two separate oil collecting grooves in the non-loaded portion of said bearing each one adapted to collect the oil at a certain direction of rotation.

3. In a device of the kind described in 65 combination, a bearing, a rotary part located in said bearing, an oil tank on said bearing, means for causing the oil to circulate between said tank and said bearing and two separate oil collecting grooves in the non-loaded portion of said bearing, each one 70 adapted to collect the oil at a certain direction of rotation, said tank being subdivided in two separate chambers.

4. In a device of the kind described in 75 combination, a bearing, a rotary part located in said bearing, an oil tank on said bearing, means for causing the oil to circulate between said tank and said bearing and two separate oil collecting grooves in the non-loaded portion of said bearing, each one 80 adapted to collect the oil at a certain direction of rotation, said tank being subdivided in two separate chambers and a connection between the said chambers. 85

5. In a device of the kind described in combination, a bearing, a rotary part located in said bearing, an oil tank on said bearing, means for causing the oil to circulate between said tank and said bearing and two separate oil collecting grooves in the non-loaded portion of said bearing, each one 90 adapted to collect the oil at a certain direction of rotation, said tank being subdivided in two separate chambers, one for the circulating oil and one for fresh oil, and a separate inlet in said first named chamber for the separate introduction of fresh oil into 95 said chamber.

In testimony whereof I affix my signature. 100

WILHELM HOLTORP.
